Primary Examiner — Antoine D Davis(74) *Attorney, Agent, or Firm* — Reinhart Boerner Van Deuren P.C.(57) **CLAIM**

The ornamental design for a right angle drive, as shown and described.

DESCRIPTION

FIG. 1 is a top perspective view of the right angle drive;
FIG. 2 is a bottom perspective view thereof;
FIG. 3 is a front view thereof;
FIG. 4 is a back view thereof;
FIG. 5 is a side view thereof;
FIG. 6 is a side view thereof showing the side opposite that shown in FIG. 5;
FIG. 7 is a bottom view thereof; and,
FIG. 8 is a top view thereof.
The dashed lines of FIGS. 1, 2, and 4-8 are for illustrative purposes only and form no part of the claimed right angle drive design.
